UNITED STATES PATENT OFFICE.

ASMUS PHILIPPSEN, OF BRIDGEPORT, CONNECTICUT.

IGNITING DEVICE.

1,044,815.

Specification of Letters Patent. Patented Nov. 19, 1912.

Application filed July 6, 1911. Serial No. 637,127.

To all whom it may concern:

Be it known that I, ASMUS PHILIPPSEN, a subject of the Emperor of Germany, residing at Bridgeport, in the county of Fairfield and State of Connecticut, have invented certain new and useful Improvements in Igniting Devices; and I do hereby declare the following to be a full, clear, and exact description of the invention, such as will enable others skilled in the art to which it app pertains to make and use the same.

This invention relates to new and useful improvements in igniting devices to be used on acetylene or gas lamps used on automobiles, motorcycles and bicycles or the like.

This invention resides in the novel constructive igniting device which may be easily applied to a lamp and which may be operated without opening the door of the lamp, thereby protecting the flame from the weather.

A further object of this invention is to provide a device of this character which when operated will create a spark to ignite the gas, but when not in use the device will automatically return to its normal position.

With these and other objects in view, my invention consists of a novel constructed device of this character which is simple in construction, strong, durable and efficient in use and which may be readily operated.

This invention consists of the novel arrangement, construction and combination of parts which will be more fully hereinafter described, claimed and pointed out in the drawing which forms part of this application and in which:

Figure 1 is a fragmentary view of an automobile lamp showing my improved igniting device applied; Fig. 2, a vertical section of the device; and Fig. 3, a side view in elevation showing the igniting member in its lowermost position.

Referring now more particularly to the drawing wherein like references indicate like parts throughout the several views, the numeral 1 indicates an ordinary gas lamp or the like such as is generally used on motor vehicles and which is provided with a burner 2 and has an opening formed in the casing of the lamp adjacent the said burner to receive the improved igniting device which is indicated generally by the numeral 3.

The igniting device 3 consists of a cylindrical member 4 having threads on the periphery thereof to receive the nuts 5 and 6,

and is adapted to be inserted in the opening formed in the casing of the lamp, the nut 5 resting on the inside of the lamp while the nut 6 is tightened up from the outside thereby forming a suitable securing means for attaching the igniting device to the lamp.

Slidably mounted in the tube 4 is a tube 7 which is of greater length than the before mentioned tube and has secured at one end thereof a bracket 8. This bracket consists of a base 9, two side members or bearing plates 10 and a rear member 11. Extending from the base 9 is a sleeve 12 which is to be placed over the tube 7 and secured to said bracket 8 by means of a nut 13 which has a threaded portion 14 to fit within the tube 7 and enlarged head portion 15 to rest on the base 9 to prevent any movement of the bracket 8. A shaft 16 is mounted in the bearing plates 10 of the bracket and has mounted thereon a friction wheel 17 that engages the pyrophorous material to be more fully hereinafter described. Loosely mounted on the shaft 16 is a pinion 18 that has a sleeve 19 extending therefrom and provided with a recess engaging a pin 20 on the shaft 16 thereby forming a suitable clutch member. A leaf spring 21 is secured by a bolt or other suitable means to the bracket and has secured to the end thereof suitable means 22 for supporting pyrophorous material that frictionally engages the friction wheel 17, thereby forming a spark to ignite the gas when said friction wheel 17 is rotated.

A suitable operating rod 23 is slidably mounted in the sleeve 7 and has a rack 24 at the end thereof to engage the pinion 18 for operating the friction wheel 17. The opposite end of the rod 23 is threaded to receive a removable handle 25. Extending perpendicularly from the nut 5 is a guide rod 26 on which is adapted to slide a perforated lug 27 of the bracket 8 that operates to prevent the rotation of the igniting device 100 and also direct the same to the flame when operated.

To automatically make the device retreat from the flame I provide in the cylindrical member 4 a coil spring 28, one end of which is secured to the cylindrical member 4 and the other to the tubing 7, which normally holds the same, as shown in Fig. 3 of the drawing and to also cause the operating rod 23 to retreat, I provide a coil spring 29 one end of which is secured to the rod 23 and the other to the tubing 7 whereby pushing

on the handle 25 of the operating rod 23 the rack 24 will engage the pinion and the clutch member on said pinion will obviously rotate the shaft 16 and cause the friction wheel 17 to engage the pyrophorous material, causing a spark and the spring 29 will automatically move the operating rod 23 downwardly and turn the pinion 16 in the opposite direction, causing the same to rotate freely on the shaft 16.

The spring 28 is to be a much weaker spring than the spring 29 so that when pushing on the operating rod 23 the casing 7 will first move toward the burner of the lamp 15 and upon further movement of the rod 23 the rack will obviously turn the pinion and cause the spark as herebefore described.

To prevent the inward movement of the tube 7 I provide lugs 30 on the end thereof 20 which engage the end of the casing 4.

It is obvious from the foregoing description that I have constructed an igniting device which will fulfil all the necessary requirements of such a device and will overcome the inconvenience of such devices now in use.

Having described my invention, what I claim as new and desire Letters Patent on is:

1. In an igniting device such as described, 30 a casing, a tube mounted in said casing, a bracket secured to the end of said tube, a shaft mounted in said bracket, a ratchet wheel keyed to said shaft, igniting material 35 engaging such ratchet, a pinion loosely mounted on said shaft and provided with a clutch to engage said shaft, an operating rod 40 slidably mounted in said tube, a rack formed on the end of said operating rod engaging said pinion to operate the same, thereby turning the shaft upon the inward movement of said operating rod, substantially as described.

2. An igniting device such as described, 45 comprising a casing secured to the casing of the lamp, a tube slidably mounted in said casing, a spring mounted in said casing for normally holding said tube in one position, a bracket mounted on the end of said tube and, an igniting device mounted in said 50 bracket, a rod for operating said igniting device mounted in said tube having a spring mounted therein for holding the said operating rod in one position, substantially as described.

3. In combination with the casing of a gas lamp having a burner therein, a tubular casing mounted in said gas lamp casing, a tubular member slidably mounted in said tubular casing and having igniting means mounted thereon, and a spring engaging 60 said tubular casing and the tubular member to normally hold said tubular member in position that the igniting device is removed from proximity with the end of the burner.

4. In combination with the casing of a gas lamp having a burner therein, a tubular casing secured to said gas lamp casing, a tubular member slidably mounted in said tubular casing, an igniting device mounted on said tubular member, a plunger slidably mounted in said tubular member and arranged to operate said igniting device, a spring secured to said plunger 70 and the tubular member and normally tending to depress the plunger, and a spring secured to said tubular casing and the tubular member and normally tending to depress the tubular member, the last mentioned 75 spring being weaker in tensile strength than the first mentioned spring so that when the plunger is moved against the resistance of the springs the tubular member is first moved into position opposite the delivery 80 end of the burner and then the igniting device is operated.

5. In an igniting device the combination with a tube, of a bracket carried thereby, a shaft mounted in said bracket, a resilient 90 secondary bracket carried by the main bracket, a securing member secured to said secondary bracket, a stick of pyrophorous material secured to said securing member, a ratchet wheel loosely mounted on said shaft 95 for co-operation with said securing member, a spring pressed rack mounted for reciprocation in said tube, a pinion mounted on said shaft, a clutch between said ratchet wheel and pinion, a sleeve mounted on said tube, 100 and nuts mounted on said sleeve for retaining the same rigid.

In testimony whereof I affix my signature in presence of two witnesses.

ASMUS PHILIPPSEN
